UNITED STATES PATENT OFFICE

2,654,319

SECTIONAL CARTRIDGE

Jack W. Roske, Crescent City, Calif.

Application December 26, 1950, Serial No. 202,692

2 Claims. (Cl. 102—44)

1

This invention relates to new and useful improvements in cartridges and the primary object of the present invention is to provide a sectional cartridge including a base cup, a shell and a novel and improved means for permanently securing the shell and cup together.

Another important object of the present invention is to provide a sectional cartridge including a plastic shell that will be converted to gas during the firing phase to assist in propelling the projectile and thereby permit reduction in the use of the propelling powder charge.

A further object of the present invention is to provide a sectional cartridge including a colored plastic shell that will indicate the type of projectile, thus eliminating the need for painting the tip of the projectile.

A still further aim of the present invention is to provide a sectional cartridge that is extremely lighter in weight than all brass cartridges and which will permit reduction in the use of critical materials such as brass, copper and zinc.

Other objects and advantages reside in the details of construction and operation as more fully hereinafter described and claimed, reference being had to the accompanying drawings forming part hereof, wherein like numerals refer to like parts throughout, and in which:

Figure 1 is an elevational view of the present cartridge;

Figure 2 is a vertical sectional view of the present cartridge and showing the shell partially inserted in the cup; and,

Figure 3 is a vertical sectional view of the shell interlocked with the cup.

Referring now to the drawings in detail, wherein for the purpose of illustration, there is disclosed a preferred embodiment of the present invention, the numeral 10 represents the completed cartridge composed of a hollow plastic shell 12 and a base or cup 14 that is fabricated of metal, such as cartridge brass, an aluminum alloy, iron, steel, or other suitable metal.

The cup 14 is formed with an inwardly tapering smoothly curved recess 16, the inner wall of which is formed with a conical depression 18. A conical lug or cam 20 is integrally formed with the cup 14 and is disposed axially within the depression 18. The lug 20 is formed with an axial bore 22 that communicates with a primer pocket 24 in the undersurface of the cup 14.

The shell 12 includes an inwardly tapered and smoothly curved lower or inner end 26 that is integrally formed with a cylindrical skirt or lip portion 28. A peripheral shoulder 30 is provided

2

about the shell 12 at its juncture with the end 26. The end 26 is formed with an axial bore or vent 32 that will register with the bore 22 when the shell is secured to the cup.

As the shell 12 is forced into the cup, the end 26 will contact the wall of the recess 16 and the cam 20 will spread the skirt 28 and force the outer surface of the skirt against the wall of the depression 18 to frictionally lock the shell and cup together. Any suitable cement may be inserted into the depression 18 to cause the skirt 28 to adhere to the wall of the depression 18.

Since the shell is constructed of plastic, the skirt 28 may be heated to a predetermined temperature before the end 26 is inserted into the recess 16 permitting flaring of the skirt outwardly by the cam 20 and the skirt to adhere to the wall of the depression 18.

The shoulder 30 will abut one end of the cup to properly seal the end 26 in the recess 16 and the body or shell 12 is constructed of colored plastic to indicate the type cartridge and thereby eliminates the necessity of coloring or painting the projectile tip 34.

The cartridge is intended primarily for use in aircraft machine guns and cannons where a reduction in weight of the individual cartridge is of great importance, allowing a greater number of rounds to be carried.

It should be noted that the metal base acts as a gas seal to the rear, preventing damage to the gun and injury to the firer. A suitable cement may be placed in the curved portion 16 of the base to form a solid and watertight band between the base and shell. This may be preferable to placing cement in the depression 18 with the possibility of getting cement in the vent, which could cause a misfire.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. A sectional cartridge comprising a plastic shell having a smoothly curved and tapered inner end, a metallic cup having a smoothly curved

and tapered recess receiving the inner end of said shell, a peripheral shoulder on the shell abutting the cup, the inner wall of said recess having a conical depression therein, an upwardly extending conical lug forming the inner wall of said depression, and a skirt at the inner end of said shell for engaging said lug to be wedgingly fitted in said depression to secure the cup to the shell as the inner end of the shell is inserted in the recess, said skirt being provided with an axial bore having a tapered upper end whose walls engage the upper end of said conical lug as the skirt is fitted in said depression.

2. A sectional cartridge comprising a plastic shell having a smoothly curved and tapered lower end portion, a skirt integrally formed with the lower end portion, a cup having a smoothly curved recess therein for receiving the lower end portion of the shell, the lower wall of said recess having a continuous groove therein, said groove having laterally and uniformly spaced inner and outer walls inclined relative to the longitudinal

axis of the cap and extending downwardly and outwardly from the recess, said skirt riding against the inner wall of said groove and against the outer wall of said groove to lock the shell and cup together as the lower end of the shell is inserted into the recess.

JACK W. ROSKE.
